UNITED STATES PATENT OFFICE.

WILLIAM E. WILD, OF DENVER, COLORADO.

ORE CLASSIFIER AND SLIMER.

SPECIFICATION forming part of Letters Patent No. 596,021, dated December 21, 1897.

Application filed January 15, 1897. Serial No. 619,298. (No model.)

To all whom it may concern:

Be it known that I, WILLIAM E. WILD, a citizen of the United States of America, residing at Denver, in the county of Arapahoe and State of Colorado, have invented certain new and useful Improvements in Ore Classifiers and Slimers; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in ore classifiers and slimers; and it consists of the features, arrangements, and combinations hereinafter described and claimed, all of which will be fully understood by reference 20 to the accompanying drawings, in which is illustrated an embodiment thereof.

In the drawings, Figure 1 is a vertical longitudinal section taken through the apparatus. Fig. 2 is a horizontal section taken on 25 the line $y-y$, Fig. 1, looking downward. Fig. 3 is a similar section taken on the line $x-x$, Fig. 1. Fig. 4 illustrates the valve mechanism for controlling the discharge from the vertical conduits, the parts being shown on a 30 larger scale.

Similar reference-characters indicating corresponding parts in the views, let the numeral 5 designate an upright tank mounted on a suitable support 6. As shown in the drawings, this tank is cylindrical in form and surrounded by hoops 7. The outer portion 5^a of the bottom of the tank is cone-shaped, while its inner part 5^b is oppositely inclined, having the shape of an inverted cone. Hence 35 the bottom of the tank is so shaped that the slimes that settle thereon may be easily drawn off from a port or ports 8, formed where the parts 5^a and 5^b of the bottom are joined together. In the center of the tank 5 is located 40 a hollow cylindrical column 9, composed of sections 9^a, set one upon another. These sections may be cast-iron and are provided with flanges 9^b, bolted together. As shown 45 in the drawings, the column 9 is composed of 50 six sections, though a greater or less number of sections may of course be employed. The bottom 9^d of the lowermost section of the col-

umn is provided with a tubular projection 10, whose lower extremity rests upon a hollow pedestal 12. To the topmost column is attached a boss 13, to which is secured a vertical shaft 14, carrying a fast bevel-gear 15, meshing with a similar gear 16 on a shaft 17, to which power is applied for rotating the column 9. Surrounding the boss 13 and attached 55 to the base thereof is a hopper 18, open to receive the material to be treated from a chute 19, leading from a stamp-mill or other pulverizing apparatus.

The wall of the hopper is provided with 60 openings close to the bottom to allow the material to escape to a downwardly-inclined circular plate 20, attached to the top flange of the uppermost section 9^a. This plate 20 may be coated with mercury for purposes of amalgamation when the material under treatment carries free gold or other amalgamable metals. To the bottom flange of the same section is attached a screen 21, having a vertical flange 21^a formed at its circumference. This screen 75 is oppositely inclined to the plate 20 and projects beyond the same, whereby it is adapted to receive the material from the plate. This material is delivered by the plate to the outer portion of the screen close to its flange 21^a, 80 whereby the said material is made to travel over the entire surface of the screen. The portion of this material too large to pass through the screen 21 is delivered through suitable openings formed in the adjacent section of the column to a hopper 22, located in the adjacent lower section of the column. A vertical pipe or conduit 23 leads from the mouth of the hopper 22 and discharges into one of the compartments 24^c of a receptacle 90 24, from which it passes by way of a discharge-pipe 25 into a stationary vat 26, divided by circular partitions 27 into a number of compartments 28, from which it may be drawn off for further treatment. The receptacle 24 95 is made fast to the depending part 10 of the column 9 and therefore rotates with the column. It is divided by radial partitions 24^a into a number of compartments 24^c equal to the number of the grades of material into 100 which the ore is to be separated by the classifying apparatus.

Each section of the hollow vertical column 9, except the lowermost, is provided with a

plate 20 and a screen 21. The uppermost screen is of coarsest mesh, and the mesh of each succeeding screen toward the bottom is finer, the bottom screen being the finest of all. 5 Hence the material that passes through the uppermost screen falls to the plate 20 next below and thence to the finer screen. The material rejected by this last-named screen passes to another hopper 22 and thence by 10 way of a pipe 23 to another compartment 24^c of the receptacle 24, from which it is taken by another pipe 25 and discharged into another compartment 28 of the vat 26, and so on, the material rejected by each screen from 15 the top toward the bottom of the column being finer and discharged by way of a hopper 22 and a pipe 23 into a separate compartment 24^c of the receptacle 24, there being as many grades of material as there are screens 21. 20 The apparatus shown in the drawings (see Fig. 1) is provided with five screens 21. Hence such a machine would classify, size, or divide the ore into five different or distinct grades or sizes, each grade being kept entirely separate while passing through the machine and finally discharged into a separate receptacle or compartment of its own. 25 The discharge extremity of each pipe 23 is controlled by a conical valve 29, attached to 30 an arm 31 and surrounding and sliding upon a vertical water-pipe 30, projecting into the pipe 23. To each arm 31 is attached a lug 31^a, through which passes a screw 32, threaded to engage a threaded aperture in a lug 9^a 35 of the lowermost section 9^a of the column 9. The valve may be raised or lowered by turning the screw 32 and the discharge from the pipe 23 regulated. It is desirable that the lower extremity of the pipe 23 shall be open 40 only wide enough to discharge the ore which enters the same; otherwise the water would flow too rapidly through these pipes.

The lower part of the hollow pedestal 12 communicates with the water-tank 33, which 45 may receive its supply from the overflow of the tank 5 or from any other suitable source having a proper pressure. The water rises in the pedestal 12 and passes through outlets 34 into the pipe 30. This upward discharge 50 of water prevents the slimes from passing downward with the sized or classified ore. It also prevents any tendency on the part of the material to clog the pipes. The volume of water passing through the pipe 30 is regulated by valves 35, whose stems 35^a are provided with hand-wheels 35^c.

The slimes, or the material so fine that it is held in suspension by the water, is allowed to settle in the bottom of the tank 5, where it 60 may be drawn off through a port or opening, as heretofore explained. The water which enters the tank is allowed to overflow at the top into a slime-tank 36, suitably supported. This slime-tank receives a grade of slimes 65 which will not settle in the tank 5 by reason of the agitation of the water incident to the rotation of the column 9 and its connections

as well as the discharge of the material into the tank 5. In this tank 36 there is very little agitation, and the slimes consequently have a 70 better chance to settle than in the tank 5. The material which settles in the tank 36 is drawn off at the bottom thereof through a port 37 and carried to any suitable receptacle, where it may be subjected to further 75 treatment by the cyanid or any other suitable process. The tank 36 has also an overflow into a tank 38, which receives a still finer grade of slimes. The entrance to the tank 38 is filled with straw or similar filtering material 39 to check the flow or current of water. The slimes which settle in the tank 38 may be drawn off through a port 40 and carried to any suitable receptacle. There is also an 80 overflow from the tank 38, which may be connected with another slime-tank, and so on, as many slime-tanks being used as are necessary to thoroughly impoverish the water of its slimes or metallic values held in suspension. The overflow from the outermost slime-90 tank may be carried by means of a suitable conduit to the water-tank 33 and thence into the pipes 23 for the purpose heretofore stated. Hence there need be no loss of water. The slimes from the tanks 5, 36, and 38 or from 95 all the slime-tanks may be drawn off and carried to a common receptacle.

Having thus described my invention, what I claim is—

1. The combination of a stationary tank 100 adapted to hold liquid, of a hollow column rotatably mounted therein, two or more inclined screens of varying mesh attached to the column one above another, said screens being downwardly inclined from their outer edges which are highest, oppositely-inclined plates also attached to the column and adapted to direct the material to the outer edges of the screens, and suitable means located within the hollow column and communicating with the individual screens for conducting the different grades of material to a suitable receptacle.

2. In an apparatus of the class described, the combination of a stationary tank having 115 an opening in its bottom, a hollow rotatable column located in said tank, projecting through the opening in the bottom thereof and resting upon a suitable support, the tank being adapted to hold liquid when the column 120 is in place, two or more conical screens attached to the column, one above another, their outer edges being highest, oppositely-inclined plates also attached to the column and adapted to discharge the material to the 125 outer edge of each screen, and conduits located within the hollow column and communicating with the individual screens at their upper extremities, while their lower extremities have outlets at the bottom of the column. 130

3. In an apparatus of the class described, the combination of a stationary tank having an opening in its bottom, a hollow rotatable column located in said tank, projecting

through an opening in the bottom thereof, and resting upon a pedestal underneath, the tank being adapted to hold liquid when the column is in place, a series of conical screens attached to the column one above another, their outer edges being highest, oppositely-inclined plates also attached to the column and adapted to direct the material to the outer edges of the screens, conduits located within the hollow column and communicating respectively with the individual screens at their upper extremities, while their lower extremities have outlets at the bottom of the column, a suitable receptacle attached to the column below the tank and divided into compartments to receive the different grades of material from the respective conduits.

4. In an apparatus of the class described, the combination of a stationary slime-tank having an opening in its bottom, a hollow rotatable column located in said tank, projecting through said opening and resting upon a suitable support underneath, a series of conical screens attached to the column one above another, their outer edges being highest, plates also attached to the column and oppositely inclined from the screens whereby they are adapted to direct the material to the outer edges of the screens, conduits located within the hollow column and communicating respectively with the individual screens at their upper extremities, while their lower extremities have outlets at the bottom of the column, a suitable receptacle attached to the column below the tank and having compartments to receive the different grades of material from the respective conduits, and a valve connected with the lower extremity of each conduit and adapted to control the discharge therefrom.

5. In an apparatus of the class described, the combination of a stationary tank having an opening in its bottom, a hollow rotatable column located therein and projecting through the bottom opening, the tank being adapted to hold liquid when the column is in place, a suitable support or pedestal located below the tank upon which the hollow column is supported, a series of conical screens attached to the column one above another, their outer edges being highest, said screens varying in mesh as described, oppositely-inclined plates also attached to the column and adapted to discharge the material to the outer edges of the screens, conduits located within the hollow column to which they are made fast, said conduits communicating respectively with the individual screens at their upper extremities, while their lower extremities are provided with outlets at the bottom of the column, a suitable receptacle attached to the column below the tank and having compartments to receive the different grades of material from the respective conduits, a conical valve adapted to project into the lower extremity of each conduit, a vertically-movable arm supporting said valve, and means for raising and lowering the arms comprising a screw passing through a lug in the arm and engaging a threaded aperture formed in a lug on the column.

6. In an apparatus of the class described, the combination of a stationary tank having an opening in its bottom, a hollow rotatable column located in said tank and projecting through said opening, a suitable support located below the tank and upon which the column is mounted, a series of conical screens of varying mesh attached to the column one above another, their outer edges being highest, oppositely-inclined plates also attached to the column and adapted to discharge the material to the outer edges of the screens, conduits located within the hollow column and communicating at their upper extremities with the individual screens, while their lower extremities have outlets at the bottom of the column, a suitable receptacle attached to the column below the tank and having compartments to receive the different grades of material from the respective conduits, suitable valve mechanism for controlling the discharge of material from the conduits, and water-pipes connected with a suitable supply source at their lower extremities, their upper extremities opening into the said conduits.

7. In an apparatus of the class described, the combination with a stationary slime-tank having an opening in its bottom, a hollow rotatable column located in the said tank and projecting through the opening in the bottom thereof, the said tank being adapted to hold liquid when the column is in place, the upper extremity of the column being suitably supported, a series of conical screens attached to the column one above another, said screens being of varying mesh, their outer edges being highest, oppositely-inclined plates also attached to the column and adapted to discharge the material to the outer edges of the screens, conduits located within the hollow column to which they are made fast, the upper extremities of said conduits communicating with the individual screens, while their lower extremities have outlets at the bottom of the column, a suitable receptacle attached to the column below the tank and adapted to receive the different grades of material from the respective conduits, a valve for controlling the discharge from the lower extremity of each conduit, a vertically-movable arm supporting said valve, and means for raising and lowering the arms comprising a screw passing through a lug in the arm and engaging a threaded aperture formed in a lug on the column.

8. In a classifier, the combination of a hollow rotatable column, a series of conical screens of varying mesh attached to said column, the mesh of the screens increasing in fineness from the top of the column downward, a series of oppositely-inclined amalgamated plates also attached to the column and adapted to discharge the material to the screens, and a separate conduit located in the hollow column to receive the discharge from each screen.

9. In a classifier, the combination of a stationary tank having an opening in its bottom, a hollow rotatable column located in the tank and projecting through said opening, a series of conical screens of varying mesh attached to the said column, the mesh of the screens increasing in fineness from the top of the column downward, a series of oppositely-inclined plates also attached to the column and adapted to discharge the material to the screens, conduits located in the hollow column and adapted to receive the discharge from the respective screens, said conduits having an outlet at the bottom of each column, a receptacle also attached to the column and located below the tank, said receptacle being divided into compartments to receive the discharge from the respective conduits, a stationary vat located below the said receptacle and divided into circular compartments, and suitable conduits leading from the respective compartments of the rotating receptacle and discharging into the corresponding compartments of the stationary vat.
10. In a combined classifier and slimer, the combination of an upright stationary tank having an inclined bottom provided with a port controlled by a suitable valve, a vertical, hollow, rotatable column located in said tank and projecting through an opening in the bottom thereof, a suitable support below the tank upon which the said column is mounted, two or more conical screens attached to the column one above another and of varying mesh, the uppermost being the coarsest, oppositely-inclined plates also attached to the column and adapted to discharge upon the screens, and suitable means for conducting the several grades of material separately from the screens through the hollow column to separate compartments of a suitable receptacle.
11. In an ore-classifier, the combination of a hollow rotatable column, conical screens attached thereto and surrounding the column, oppositely-inclined plates also attached to the column and adapted to feed the ore to the outer edge of the screens which are provided with upwardly-projecting flanges, conduits located within the hollow column and adapted to receive the material from the respective screens, and pipes projecting upward into the lower extremities of the respective conduits, said pipes being connected with a suitable water-supply source having sufficient pressure to force the water through the said pipes into the conduits.
12. In a combined ore classifier and slimer, the combination of a stationary tank, the rotatable column located therein, conical screens of varying mesh attached to the column and located one above another, the uppermost being of the coarsest mesh, and one or more slime-tanks connected with the main tank and adapted to receive the overflow therefrom.
13. In a classifier for ore or other material, the combination of a stationary tank having an opening in its bottom, a hollow rotatable column located in said tank and projecting through the opening in the bottom thereof, a series of screens of varying mesh attached to said column, conduits located within the column, their upper extremities communicating with and being adapted to receive the material rejected by the respective screens, the lower extremities of the conduits having suitable outlets located at or below the opening in the bottom of the tank.
14. In a classifier for ore and other material, the combination of a stationary tank having an opening in the bottom, a hollow rotatable column located in said tank and projecting through said opening in the bottom thereof, the tank being adapted to hold liquid when the column is in place, a series of screens of varying mesh attached to said column, conduits located within and attached to the column, their upper extremities communicating with and being adapted to receive the material from the screens, the lower extremities of the conduits having suitable outlets located at or below the opening in the bottom of the tank, and suitable means for introducing water under pressure into the discharge extremities of the conduits to prevent the slimes from passing downward with the ore.
15. In an ore-classifier, the combination of a stationary tank having an opening in its bottom, of a hollow rotatable column located in said tank and projecting through said opening, suitable classifying or grading mechanism attached to the exterior surface of the column, conduits located within the column and adapted to receive the respective grades from said mechanism, the conduits having outlets below the bottom opening in the tank.

In testimony whereof I affix my signature in presence of two witnesses.
